UNITED STATES PATENT OFFICE.

OZRO N. WISWELL, OF LOS ANGELES, CALIFORNIA, ASSIGNOR TO SWINGSPOUT MEASURE COMPANY, A CORPORATION OF CALIFORNIA.

CONICAL-VALVE SWING-SPOUT PACKAGE.

Application filed June 7, 1922. Serial No. 566,648.

This invention relates to packages for containing liquid substances and particularly to containers in which lubricating oils are sold.

5 It is the principal object of the invention to provide an oil package of this character having a new and improved form of turnable pouring spout equipped with a valve which is adapted to open, thus permitting a free flow of oil, when the spout is swung into pouring position, and which is adapted to close, so as to prevent the escape of oil from the container, when the spout is in retracted position.

15 It is also an object of the invention to provide a simple form of valve for such a device which may be equipped with gaskets for forming a perfect seal between the rotatable parts thereof.

20 The specific advantages of the invention, and further objects thereof, will be made evident hereinafter.

Fig. 1 is a perspective view showing one form of my invention in use upon a lubricating oil package.

Fig. 2 is a fragmentary vertical section through the swingspout device and the upper portion of the container upon which it is mounted.

30 Fig. 3 is a plan view of a container having another form of my invention mounted thereupon.

Fig. 4 is a section taken upon the plane indicated by the line 4-4 of Fig. 3, the spout being extended laterally in this view.

35 Fig. 5 is a sectional view illustrating the separate parts from which the swingspout device shown in Fig. 3 is formed, before their assembly.

40 The embodiment of my invention illustrated in Figs. 1 and 2 comprises a conical shell 11 which is stamped from sheet metal in such a manner that when it is mounted upon the top 12 of a container 13, the axis 45 *a-a* thereof will be disposed at an angle substantially as shown. A cup 15, having an opening 16 therein, adapted to coincide with an opening in the conical member 11, is placed over the conical member 11 and has 50 a pouring spout 17 extending therefrom at substantially right angles to the axis *a-a*, so that when the spout 17 is swung as indicated by the arrow 19 in Fig. 1, it will pass upwardly through an inclined plane 55 and through the position indicated by dotted

lines 20 to the retracted position indicated by the dotted lines 21.

Disposing the axis, upon which the spout swings, at an angle to the top 12 provides a means whereby the spout may be brought to rest upon the top of the container when it is not in use, any pressure which may be exerted upon the spout when it is in closed position being received by the top 12, thereupon causing no strains or distortion to be incurred in the conical members 11 and 15.

One of the features of the invention resides in the manner in which a perfect seal is maintained between the two conical members. It will be perceived that the cup 15 is slightly longer than the conical shell 11, and that a space 23 exists between the end 24 of the shell and the head 25 of the cup. When the securing means 27, which consists of an outwardly pressed projection, is riveted down as shown in Figure 2, the head 25 is flexed inwardly. The tendency for the head 25 to assume its original extension through a flat plane causes a force to be exerted which holds the cup 15 tightly down upon the shell 11. After the valve parts are assembled, they are dipped in hot paraffine, or some other similar substance, which enters between the engaging surfaces of the tubular shell and the cup and congealing therebetween provides a seal against the passage of liquid other than through the spout 17 when it is brought into the proper pouring position.

55 This swingspout is very simple of construction, being comprised of only three parts, which are of extremely simple and rugged form, permitting them to be formed from lightweight sheet metal.

The device shown in Fig. 1 is intended for use upon containers in which comparatively viscous substances such as engine lubricating oils are carried. In Figs. 3, 4, and 5, I illustrate a form of my invention having gaskets between the shell 35 and the cup 36 so that a very effective seal is formed therebetween which would prevent the escape of lighter fluids. The conical member 35 is adapted to be soldered into the top 37 of the container 38 and is so formed that the axis thereof extends substantially perpendicular. The extremely broad formation of the shell 35 and the cup 36 permits a very large pouring opening 39 to be employed, this opening being directly ex- 110

posed to the interior of the container 38. The spout 40 used with this device is of quadrilateral form to conform to the shape of the opening 39 provided in the member 35 and is mounted upon the cup 36 in open communication with the opening 41 provided therein.

As shown in the Figs. 4 and 5 a gasket 45 is placed between the top 46 of the shell 35 and the head 47 of the cup 36, the head 47 being forced inwardly thereagainst when the projection 48 is riveted down as indicated at 49 in Fig. 4. The gasket 51 is of conical form and is placed between outwardly flared lower edge 52 of the cup 36 and the lower edge 53 of the member 35, which is similarly flared. It will be perceived that as cup 36 is forced downwardly upon the member 35, the gasket 45 will be gripped as hereinbefore explained and the pressure will also be brought to bear upon the gasket 51 due to the increased angularity of those portions of the members 35 and 36 between which the gasket 51 is placed. When the spout 40 is in the position shown in Fig. 3 the openings 39 and 41 in the members 35 and 36 are oppositely disposed so that the outlet of liquid through the pouring device is obstructed. When it is desired to pour from the container 38, the spout 40 may be swung either to the right or to the left into the extended position in which the openings 39 and 41 coincide and permit a free flow of liquid from the container.

The valves herein disclosed should be sufficiently tight for all practical purposes when paraffined as described, as the overlapping surfaces between the valve openings are very broad. Furthermore, the conical shape of the valve members provides a very rugged construction and a simplicity in form which contributes greatly to the cheapness of their manufacture.

45 I claim as my invention:—

1. In a swingspout pouring device for a container, the combination of: a shell adapted to be secured to the top of a container; an inverted cup rotatably mounted on said shell, and pressurably held thereagainst; and a spout extending from said cup and secured against rotation relative thereto, the axis of rotation of said cup, when mounted on a container, lying in a vertical plane and in a plane which is at an angle to a horizontal plane.

2. With a container, the combination of: a conoidal body extending outwardly from said container, said body having an opening communicating with the interior of said container; a cup fitting over said body, said cup having an opening therein adapted to coincide with said opening in said body, said cup having its interior of conoidal form to correspond to said body and being of

greater length than said body so that a space exists between the top of said body and head of said cup; and means comprising an extension of said body passing through said head pressurably holding said cup against said body.

3. In a swingspout device for containers the combination of: a cup comprising a conical side wall having an opening therein and a head across the small end thereof; a pouring means upon the exterior of said cup and in communication with said opening; a conical shell fitting within said cup, having an opening adapted to coincide with said opening in said cup; and means for mounting said shell in an angular position upon a container so that said pouring means will swing through a plane inclined to the wall of said container upon which said device is mounted.

4. In a swingspout device for containers the combination of: a cup comprising a conical side wall having an opening therein and a head across the small end thereof; a pouring means upon the exterior of said cup and in communication with said opening; a conical shell fitting within said cup, having an opening adapted to coincide with said opening in said cup; means for holding said cup upon said shell; and means for mounting said shell in an angular position upon a container so that said pouring means will swing through a plane inclined to the wall of said container upon which said device is mounted.

5. In a swingspout device for containers, the combination of: a cup having an opening therein and a head across the closed end thereof; a pouring means upon the exterior of said cup and in communication with said opening; a shell fitting within said cup, having an opening adapted to coincide with said opening in said cup; and means for mounting said shell in an angular position upon a container so that said pouring means will swing through a plane inclined to the wall of said container upon which said device is mounted.

6. In a swingspout device for a container: a conoidal shell; a conoidal cup rotatably mounted on said shell and carrying a spout, said cup being adapted to be turned from open to closed position and vice versa relative to said shell; and means pressurably holding said cup against said shell while said cup is turned from open to closed position relative to said shell, the axis of said cup being inclined to both a horizontal plane and a perpendicular to the horizontal plane when said cup is mounted on the container.

In testimony whereof, I have hereunto set my hand at Los Angeles, California, this 2nd day of June, 1922.

OZRO N. WISWELL.
